UNITED STATES PATENT OFFICE.

LYMAN R. ROBERTS, OF RUTHERFORD, NEW JERSEY, ASSIGNOR, BY MESNE ASSIGNMENTS, TO L. R. ROBERTS TYPEWRITER COMPANY, OF STAMFORD, CONNECTICUT, A CORPORATION OF DELAWARE.

TYPEWRITER.

Application filed November 19, 1918. Serial No. 263,116.

To all whom it may concern:

Be it known that I, LYMAN R. ROBERTS, a citizen of the United States, residing at Rutherford, county of Bergen, and State of New Jersey, have invented certain new and useful Improvements in Typewriters, fully described and represented in the following specification and the accompanying drawings, forming a part of the same.

10 This invention relates to improvements in typewriters.

It is the principal object of the invention to provide a typewriter such that the type bars may be readily removed from the machine, for the purpose of substitution or the like, and readily replaced in operative relation with their operating mechanisms.

With this general object, and others which will be obvious to those skilled in the art, 20 in view, the invention consists in the features, details of construction and combinations which will first be described in connection with the accompanying drawings, and then more particularly pointed out.

25 In the drawings—

Fig. 1 is a view in side elevation of a typewriter constructed in accordance with the invention;

Fig. 2 is a view of the same in rear elevation with parts broken away;

Fig. 3 is a cross sectional view taken on the broken line 3—3 of Fig. 1.

Fig. 4 is a view in vertical cross section.

Fig. 5 is a view in horizontal section showing a portion of the case-shift mechanism;

Fig. 6 is a cross sectional view taken on the line 6—6 of Fig. 5; and

Fig. 7 is a cross sectional view taken on the line 7—7 of Fig. 3.

Referring to the drawings, there is provided a set of type bars and a set of operating mechanisms, each type bar being freely removable from its corresponding operating mechanism when in a position of rest, and

locked thereto during operation. In structures embodying the invention to the best advantage the operating mechanisms include members having sliding contact with the type bars to actuate the same. Although

capable of various constructions, in the embodiment illustrated, there is provided a set of type bars 11 bearing the type characters

12. Each type bar, pivotally mounted, as

hereinafter described, normally rests on an arcuate support 13 secured to the frame 14 of the machine.

These type bars are swung upwardly by operating mechanisms including a set of keys 15 which form the key board of the machine. As shown, the keys are carried on key levers 16 having their outer arms so arranged as to locate the keys in three horizontal banks, as shown in Fig. 4. In order that the key levers may have an equal throw they are pivoted on three different cross rods. The key levers of the outer bank are pivoted on a forward cross rod 17, those of the intermediate bank on an intermediate cross rod 18, and those of the inner bank on a rear cross rod 19. The key levers are held in their normal position by a stop plate 20.

Pivottally mounted, as hereinafter described, is a set of sublevers 21. Each of these operating or sub levers is provided with a pin 22 bearing against the under side of the corresponding type bar. It will be seen that when the sublever 21 is swung upwardly the engagement of the pin 22 with the type bar will cause the latter to be swung upwardly for its printing stroke, the pin having a sliding engagement with the type bar during this operation. The sublevers 21 are actuated by means of the key levers 16 and to this end, each key lever is connected with its corresponding sublever by a link 23. As shown, this link is in the form of a wire, hooked through holes in the two levers. Although the various links 23 perform the same functions, it will be obvious that, as the key levers are in a horizontal bank and the sublevers in an arcuate bank, the links will vary in length and configuration according to their position.

To lock a type bar and its operating mechanism together during operation, each type bar is provided with an arm 24 forming an open ended slot 25. As will be seen from Fig. 4, when the parts are in a position of rest, this slot terminates just short of the pin 22. When, however, the key lever is operated, the upward swing of the parts causes the pin to enter the slot and the two levers are thus locked together until their return to the position of rest.

With the construction described, the type bars may be readily removed from the oper-

ating mechanisms, when in a position of rest, as there is no connection between them, and they are locked together during operation. This construction provides, further, a prop-
5 erly effective acceleration in the type bar action. Furthermore, there is no torsion on the type bar itself, which aids in maintaining alignment.

The invention includes in its entirety a
10 removable mount for the type bars, a fixed mount for the sublevers, and means for positioning the removable mount in the frame of the machine. In structures embodying the invention to the best advan-
15 tage, the type bars and sublevers are mounted so as to swing in radial planes having a common centre. Although capable of various constructions, in that here illustrated, the type bars are carried by a removable
20 mount in the form of a segment 30, provided with a plurality of radial slots 31 in which the type bars are pivoted. To this end, as appears more clearly in Fig. 4, each type bar is formed, at its inner end with
25 a rounded portion which is inserted in one of the slots 31 and which has a central opening for the passage of a common pivotal wire 32. This pivotal wire is concentric with the segment and is seated in the bot-
30 tom of a V-shaped groove 33 formed in the outer edge of the segment 30. The mount or segment 30 also carries means for returning the type bars to normal position. To this end, attached to each type bar is a
35 coil spring 34, the other end of which is secured to a bracket 35 screwed or otherwise attached to the back face of the seg-
ment 30.

As before stated, means is provided for
40 positioning the removable segment 30 in the frame. As shown, the frame is formed at each side with an internal shoulder 36 providing supporting uprights between which the type bar segment is hung. In the face
45 of each of these two shoulders is set a dowel 37. Cooperating with these supporting up-
rights are yokes 38 secured to the end faces of the segment 30 and forming supporting projections by means of which the segment
50 is hung in the frame. The yokes 38 are orificed to take over dowels 37, as more clearly appears in Fig. 3.

When the yokes 38 are slipped over the
55 dowels 37 the segment is hung between the supporting uprights and is definitely posi-
tioned, and means is provided for securing it in this position. Although capable of various constructions, as here shown, threaded through the frame of the machine, at each
60 side, is a pointed thumb screw 39. This is adapted to pass through an opening in the side plate of the yoke 38 and to enter the V-shaped groove 33, as more clearly appears in Fig. 7. It will be seen that when the
65 two screws are tightened up, their points,

entering the V-shaped groove 33, securely clamp the segment in position.

For mounting the sublevers 21, as here illustrated, below the removable segment 30, is a fixed segment 40 concentric with seg-
70 ment 30 and secured to the frame by screws 41 or the like. This segment is formed with a plurality of spaced radial slots 42 which have a centre common with the center of the slots of the removable segment. In each of these slots 42 is pivoted one of the sublevers 21. The levers are pivoted on a common pivotal wire 43 which is concentric with the pivotal wire 32 of the type bars and which has its seat in the bottom of a recess 44 80 formed in the front face of the segment.

It will be seen that with the construction described, removal and insertion of the bank of type bars, for substitution or the like, are extremely simple operations. By loosening the thumb screws 39, the removable segment, carrying the type bars, is free to be lifted out, the individual type bars being freely separable from their operating mechanisms, as before described. In replacing the same or a substitute set, it is only necessary to slip the yoke members over the dowels 37, thus positioning the mount or segment, and tighten the thumb screws 39. There is no necessity for any careful adjustment or intricate manipulation. No connections or the like have to be made between the type bars and their operating mechanisms, and with the type bar segment mounted in the frame as described, the removal and insertion of type bar units is effected without loss of alignment.

In the embodiment of the invention here illustrated each type bar carries three type characters and there is provision for a 105 double case-shift to shift the platen and its carriage into an extreme or an intermediate position in accordance with the type character to be used. To this end, forming part of the key board, are two case-shift levers 110 50, 51. The lever 50 for the extreme case-shift is pivotally mounted on a tie rod 52 near the rear of the machine and the intermediate case shift lever 51 is mounted to swing on a rock shaft 53.

The platen 54 has its shaft journalled in the end pieces 55 of a carriage 56, which is mounted to have the usual reciprocating movement, by means of two sets of ball bearings 57 riding in grooved rails 58 on the carriage and a doubly grooved guide 59. This carriage guide 59 is supported by upwardly extending arms 60 formed on a carriage truck in the form of a rigid plate 61. To give the plate carriage case-shift movement, this truck is mounted on two vertically reciprocating plungers 62 sliding in cylindrical bearing members 63 cast on the frame at the rear corners. In order that operation of the case-shift levers may cause 130

the plungers to raise the platen carriage, the plungers are connected by a cross bar 64, beneath which extends a lifting lever 65. This lifting lever is keyed or otherwise secured to the rock shaft 53. Also secured to the rock shaft is an operating lever 66 over which extends a lug 67 formed on the case-shift lever 50 and a similar lug 68 formed in the case-shift lever 51. It will be seen that on the depression of either case-shift lever, its lug will engage the operating lever 66 thus rocking shaft 53, and this in turn causes the lifting lever 65 to engage the cross bar 64 and raise the plungers 62, thus shifting the vertical position of the platen carriage. The limit of movement for the extreme case-shift is fixed by the engagement of the cross bar 64 with a washer or ring 69 secured to the frame. To make this limit of movement adjustable, the washer 69 is wedge-shaped and is secured to the frame by screws passing through arcuate slots 70. By shifting the washer 69 on its centers a greater or less amount of metal is interposed in the path of the cross bar and the movement allowed is decreased or increased accordingly.

For the intermediate case-shift, a spacing lug is interposed between the cross bar and the washer to fix the movement of the plungers. To this end, in the present embodiment, the case-shift lever 51 has a rearwardly extending arm 72 carrying a pin 73 which rides in a slot 74 formed in a movable plate 75. This plate has a second slot 76 which rides over two aligned pins 77. With this construction, operation of the case-shift lever causes a rearward, horizontal movement of the plate 75. This plate carries a spacing lug 78, so arranged as to be interposed between the cross bar and the washer 69 when the plate is moved by operation of the case-shift lever. It will be seen, therefore, that the case-shift lever 51 will cause the carriage to be moved to an intermediate position only, as it is limited by the engagement of the cross bar with the spacing lug. Adjustment may be made also for this case-shift by movement of the washer 69 as above described.

In order to prevent "bouncing" of the platen carriage during operation of the machine, there is provided means for locking the carriage against raising movement, and in structures embodying the invention to the best advantage, a locking member is normally interposed between the carriage raising mechanism and a fixed abutment. Although capable of various constructions, as shown, on a cross shaft 80 are mounted locking plates 81 provided with shoulders 82 which normally take over the cross bar 64. The upper end of each locking plate is in close proximity to a fixed abutment 83 formed on the frame of the machine. The locking plates 81 are normally held in locking position by means of a spring 181 secured at one end to the shaft 80 and at the other end to the frame of the machine. With these locking plates interposed between the fixed abutment and the removable cross bar, the carriage is made substantially solid with the frame and any "bouncing" of their sublevers together.

Means is provided for removing the locking plates to permit case-shift movement of the platen carriage, and in structures embodying the invention to the best advantage, the locking plates are caused to be removed from locking position upon operation of either of the case-shift levers. As here shown, as an example, on the pivotal shaft 80 of the locking plates, is mounted a dog 84 having a rounded shoulder taking over a pin 85 on the operating lever 65. When the rock shaft is operated by the action of either case-shift lever, the consequent movement of operating lever 65 causes pin 85 to swing the dog 84 rearwardly. This movement of the dog, through shaft 80, causes the locking plates to swing out of the way, thereby permitting elevation of the plungers and the platen carriage. Upon return of the carriage to normal position the locking plate again moves into locking position by means of its spring 181.

In the construction here illustrated, the cross bar 64 which connects the two plungers 62 serves as an assembling member for connecting the platen carriage with the frame, and is readily removable to permit removal of the carriage. Means is also provided for holding the cross bar in place without interfering with its ready removal. Although capable of various constructions, as here shown, the cross bar 64 passes through holes formed in the plungers 62 of a size to permit its ready removal and insertion. The cross bar, when in place, extends out some distance beyond the plungers, as appears in Fig. 2. Near each end, it is provided with a circumferential groove to receive a spring pressed securing member. In the present embodiment this securing member also serves as a balancing member for the carriage. As shown, pivoted on a pin 86, at each side of the machine, is a bell crank lever 87, the lower arm of which extends below the cross bar 64 and takes into the groove above mentioned. The upper arm of the bell crank 87 is notched to adjustably receive the end of a coil balance spring 88, the other end of which is secured to the machine frame. With the construction described, the cross bar is held in place by the balancing members and to remove the cross bar it is only necessary to swing down the bell cranks away from the cross bar. Furthermore, this construction, with a balancing mechanism at each side, provides

4
a more even balance, as the weight shifts with the travel of the carriage. It is noted that upon removal of the cross bar 64 and a screw 89 in the back space mechanism 5 190, the carriage is free for removal from the frame.

The above described case shifting features are claimed in a copending divisional application, Ser. No. 383397.

10. What is claimed is:

1. In a typewriter, and in combination, a relatively stationary frame having supporting uprights, a readily removable type bar segment in which the type bars are pivotally mounted, hung between the supporting uprights and having supporting projections which cooperate with the supporting uprights, operating members for the type bars separate therefrom and normally 20 engaging the same from below, whereby the type bars are, while in a position of rest, freely separable from their respective operating members when the segment is removed, means for positioning the supporting 25 projections upon the supporting uprights, and means for securing the segment in position.

2. In a typewriter, and in combination, a relatively stationary frame having supporting uprights, a readily removable type bar segment in which the type bars are pivotally mounted, hung between the supporting uprights and having supporting projections which cooperate with the supporting 30 uprights, sublevers separate from the type bars and normally engaging the same from below, whereby the type bars are, while in a position of rest, freely separable from their respective sublevers when the 35 segment is removed, key levers, and operative connections between the key levers and the sublevers.

3. In a typewriter, and in combination, a relatively stationary frame having supporting uprights, a readily removable type bar segment hung between said supporting uprights and having supporting projections which cooperate with the supporting uprights, type bars pivotally mounted in said 40 segment, operating members for the type bars, separate therefrom and normally engaging the type bars from below, whereby the type bars, while at rest, may be lifted away from the operating members upon removal of the segment, and means for locking the type bars and their operating members together during operation.

4. In a typewriter, and in combination, a relatively stationary frame having supporting uprights, a readily removable type bar segment, hung between said supporting uprights and having supporting projections which cooperate with the supporting uprights, type bars pivotally mounted in said 45 segment, sublevers for the type bars sep-

arate from the type bars and having pins normally engaging the type bars from below, whereby the type bars are, while in a position of rest, freely separable from their respective sublevers when the segment is removed, and arms on the type bars forming open ended slots embracing said pins during operation, thereby to lock the type bars and their sub-levers together.

5. In a typewriter, and in combination, a relatively stationary frame having supporting uprights, said uprights having flat, horizontal supporting surfaces, a readily removable type bar segment, hung between said supporting uprights and having supporting projections which engage said surfaces, cooperating locating elements carried by said projections and said uprights for locating the segment in a given position, operating members for the type bars, said type bars and operating members having mutually engaging contact surfaces freely separable upon removal of the segment and brought into operable relation upon locating the segment in position, and means for removably securing the segment in the located position.

6. In a typewriter, and in combination, a relatively stationary frame having supporting uprights, a readily removable type bar segment hung between said supporting uprights and having supporting projections which cooperate with the supporting uprights, type bars pivotally mounted in said segment, operating mechanisms for the type bars and so arranged that the type bars are freely separable from the operating mechanisms when the segment is removed, dowel and socket connections for positioning the supporting projections on the supporting uprights, and readily accessible thumb screws for locking the segment in position.

7. In a typewriter, and in combination, a relatively stationary frame having supporting uprights, a readily removable type bar segment hung between said supporting uprights and having supporting projections which cooperate with the supporting uprights, type bars pivotally mounted in said segment to swing in radial planes having a common center, a set of operating members for the type bars, a fixed segment in which the operating members are mounted to swing in radial planes having a common center, the type bars being freely separable from the operating members when the type bar segment is removed.

8. In a typewriter, and in combination, a relatively stationary frame having supporting uprights, a readily removable type bar segment, hung between said supporting uprights, and having supporting projections which cooperate with the supporting uprights, a fixed segment carried by the frame, each of said segments having a plu-

rality of radial slots struck from a common center, type bars pivoted in the slots of the removable segment, sublevers pivoted in the slots of the fixed segment, the type bars being freely separable from the sublevers when the removable segment is removed, key levers, and operating connections between the key levers and the sublevers.

9. In a typewriter, and in combination,
10 a relatively stationary frame having supporting uprights, a readily removable type bar segment hung between said supporting uprights and having supporting projections which cooperate with the support-

ing uprights, a fixed segment carried by the 15 frame, each of said segments having a plurality of radial slots, type bars pivoted in the slots of the removable segment, sublevers pivoted in the slots of the fixed segment, the type bars being freely separable from the 20 sublevers when the removable segment is removed, key levers, and operating connections between the key levers and the sublevers.

In testimony whereof, I have hereunto set 25 my hand.

LYMAN R. ROBERTS.

Certificate of Correction.

It is hereby certified that in Letters Patent No. 1,450,115, granted March 27, 1923, upon the application of Lyman R. Roberts, of Rutherford, New Jersey, for an improvement in "Typewriters," an error appears in the printed specification requiring correction as follows: Page 8, line 74, strike out the words "their sub-levers together" and insert instead *the carriage is prevented*; and that the said Letters Patent should be read with this correction therein that the same may conform to the record of the case in the Patent Office.

Signed and sealed this 29th day of May, A. D., 1923.

[Seal.]

KARL FENNING,
Acting Commissioner of Patents.
